CLAIM

The ornamental design for a contact point, as shown and described.

DESCRIPTION

FIG. 1 is a perspective view of a contact point;

FIG. 2 is a first side view thereof;

FIG. 3 is a second side view thereof;

FIG. 4 is a third side view thereof;

FIG. 5 is a fourth side view thereof;

FIG. 6 is a top view thereof; and,

FIG. 7 is a bottom view thereof.

The dashed broken lines in the figures illustrate portions of the contact point that form no part of the claimed design.

1 Claim, 2 Drawing Sheets
